O. SHEEHAN.
FIBER DECORTICATING MACHINE.
APPLICATION FILED DEC. 4, 1907.

Patented Jan. 27, 1914.

2 SHEETS—SHEET 2.

UNITED STATES PATENT OFFICE.

OWEN SHEEHAN, OF NEW BEDFORD, MASSACHUSETTS, ASSIGNOR TO THE HOLLINGS-WORTH AND VOSE COMPANY, OF BOSTON, MASSACHUSETTS, A CORPORATION OF MASSACHUSETTS.

FIBER-DECORTICATING MACHINE.

1,085,228.

Specification of Letters Patent.

Patented Jan. 27, 1914.

Application filed December 4, 1907. Serial No. 405,110.

To all whom it may concern:

Be it known that I, OWEN SHEEHAN, a citizen of the United States, residing at New Bedford, in the county of Bristol and State of Massachusetts, have invented certain new and useful Improvements in Fiber-Decorticating Machines; and I do hereby declare the following to be a full, clear, and exact description of the invention, such as will enable others skilled in the art to which it appertains to make and use the same.

My invention relates to decorticating machines for disintegrating and cleaning fiber from fibrous plants.

It has for its object to accomplish this work in a more efficient and practical manner and to obtain a better product than has heretofore been produced.

The invention contemplates the thorough scraping and washing of the fibrous material in addition to the operations performed by the machine described in my patent granted November 21, 1911 Number 1,009,589.

The invention consists in the features of construction and combinations of parts hereinafter described and specified in the claims.

In the accompanying drawings, illustrating the preferred embodiment of my invention: Figure 1 is a broken side elevation of the machine. Fig. 2 is a plan view, and Fig. 3 is a detailed view of a fragment of one of the endless aprons and a part of one of the chains secured to its edge.

In carrying out my invention, I employ toothed bars 1 suitably mounted on one end of the supporting frame 2 of the machine and adapted to be turned to either a horizontal or vertical position for splitting fibrous substances of different lengths by

means of a handle 2a substantially as shown and described in my pending application referred to herein. The teeth on each bar are spaced differently from those on the other bars. Pairs of fluted or draft rolls 3 and

45 tooth-bearing cleaning rolls 4 are arranged in succession, the fluted rolls being placed between the combs and the cleaning rolls. Next in order are upper and lower scraper aprons 5 and 6, preferably made of a rubber mesh material, mounted on rollers 7, 8 and 9, 10 respectively. The upper rollers 7 and 8 are mounted in bearings 11, 12 adjustable vertically by means of the set screws 13, 14. Each of the aprons carries transverse bars

in cross section, and are arranged equidistant apart. The bars 15 on the upper apron fall midway between adjacent bars 16 on the lower apron. The object of the vertical adjustment of the bearings 11 and 12 of the upper apron-carrying rollers 7 and 8 is to regulate the degree of mesh between the bars on the two aprons. The form of said bars permit them to act more efficiently upon the fibrous material passed between them than do the usual straight strips and there is no danger of injuring said material.

The shafts on which the rollers 7, 8, 9 and 10 are mounted also carry pairs of sprocket wheels 17, 18, 19 and 20. The sprocket wheels 17 are mounted on the opposite ends of the roller 7 inside of its bearings while the other sprocket wheels are similarly arranged with relation to the other rollers 8, 9 and 10. A sprocket chain 21 passes over one of the sprocket wheels 17 and one of the sprocket wheels 18, another sprocket chain 22 passes over the other ones of said wheels 17 and 18, and the sprocket wheels 19 and 20 of the lower rollers are similarly provided with sprocket chains 23. Each chain runs along one edge of one of the aprons and is provided about every six inches with a special link 25 having laterally projecting lugs 26 which are secured to the edge of the apron. By this means the aprons are positively driven and do not have to depend upon frictional contact with their rollers to maintain the V-shaped bars on one apron in proper relation to those on the other apron. Meshing gears 27 and 28, mounted respectively on the shafts carrying the rollers 8 and 10, serve to drive said sprocket wheels.

At the end of the aprons there is arranged a pair of plain delivery rolls 29, 30, preferably made of wood. The speed of these rolls is much higher than the speed of the aprons whereby the fiber when engaged with said rolls is drawn over the rods carried by said aprons and given an additional scraping before it is dropped upon the floor.

All of the rolls and the aprons are driven from the main drive shaft 31 carrying a pulley 32 and a gear wheel 33. The pulley 32 is connected up with a pulley 34 on an auxiliary shaft or spindle 35 by means of the belt 36. The gear wheel 33 meshes with a gear 37 on the shaft of the apron carrying roller 10. On the auxiliary spindle 35 there are mounted two pulleys 38 and 39, the

former of which carries a belt 40 also passing over a pulley 41 on the shaft of the lower fluted roll, and the latter of which carries a belt 42 running over the pulley 43 on the 5 shaft of the lower cleaning roll. The delivery rolls carry meshing gears 44 and 45. The lower one of said delivery rolls also has a pinion 46 which meshes with the gear wheel 33 on the main drive shaft. It will 10 be noted that the ratios between the various drive pulleys are such that each successive pair of rolls and the aprons are revolved at a greater speed from the fluted rolls to the delivery rolls.

15 A portable water tank 47 is fitted snugly under the machine frame and is divided into two compartments 48 and 49 by a screen 50. A pipe 51 leads from the compartment 49 to a pump 52. Another pipe 53 leads from 20 said pump and extends longitudinally above the machine. The under surface of said pipe is perforated to deliver a shower upon the fluted rolls, cleaning rolls and scraper aprons. The latter are made of rubber 25 mesh material to permit the water showered upon them to pass freely through to the tank below, rubber being preferably used because it is less effected by moisture, whereas metal would rust and textile fabric rot.

30 When the machine is in operation, the ends of the plants or leaves are fed between the fluted rolls, the leaves being split by the toothed bars or combs when desired. The material then passes between the cleaning 35 rolls which cut into and throw off the pulpy matter. From thence the material passes between the scraper aprons and finally through the delivery rolls. During the operation of the machine, the pump is operated 40 by suitable mechanism and draws the water from compartment 49 of the tank 47 and forces it through the perforated pipe 53. The shower from said pipe falls upon the fluted rolls, cleaning rolls and aprons, to 45 soften and wash the pulpy matter, into the compartments 48 of the tank thereby keeping said rolls and aprons clean and free from said pulpy matter which would otherwise adhere thereto. The pulpy matter remains 50 in this compartment while the water passes through the screen 50 into the compartment 49 and is used over again. The water falling from the pipe 53 passes freely through the meshes of the material of which the 55 aprons are made.

I claim:

1. A machine of the character described comprising a toothed bar arranged at the feeding end of the machine, means to turn

said bar to bring its teeth into operative 60 position for splitting the fiber-bearing substances, a pair of cleaning rolls, a pair of draft rolls arranged between said toothed bar and cleaning rolls for drawing said substances across said bar, a pair of endless 65 scraper aprons located at the delivery side of said rolls, a pair of delivery rolls arranged at the other end of said aprons, and means to drive said aprons at a greater speed than said cleaning rolls, and said delivery rolls 70 at a greater speed than said aprons for drawing the fiber out from its pulley coating which is separated and withheld by said cleaning rolls and scraper aprons.

2. In a decorticating machine, the combination, with cleaning and scraping apparatus, of a shower pipe arranged over the same, a tank located below the same for catching the water and pulpy matter washed from said cleaning and scraping apparatus, 80 means for conveying the water from said tank to said shower pipe, and means to strain the water in said tank before it enters said shower pipe.

3. In a machine of the character described, the combination, with a pair of scraper aprons made of rust proof mesh material and having scraper bars mounted thereon, for the purpose specified, said aprons being arranged one above the other, 90 of means to turn said aprons in opposite directions so that the adjacent portions thereof travel in the same direction, means to feed material between said aprons, and a shower pipe arranged above and extending over said 95 aprons and adapted to deliver water thereon for the purpose specified.

4. In a machine of the character described, the combination, with cleaning rolls, draft rolls and scraper aprons, the latter being arranged one above the other, of means to turn said aprons in opposite directions so that the adjacent portions thereof travel in the same direction, said aprons being made of rust proof mesh material and having 100 scraper bars mounted thereon, said cleaning rolls being arranged between said draft rolls and aprons, and means to actuate said rolls, of a shower pipe arranged above and extending over all of said rolls and aprons and 110 adapted to deliver water thereon for the purpose specified.

In testimony whereof, I affix my signature, in presence of two witnesses.

OWEN SHEEHAN.
